FOREIGN PATENT DOCUMENTS

EP 2 196 277 A1 6/2010

* cited by examiner

Primary Examiner — Ian Simmons*Assistant Examiner* — Richelle G Shelton(74) *Attorney, Agent, or Firm* — Collard & Roe, P.C.(57) **CLAIM**

The ornamental design for a display screen with graphical user interface, as shown and described.

DESCRIPTION

The sole FIGURE shows a front view of our design for a display screen with graphical user interface.

The broken line showing of a display screen forms no part of the claimed design.

1 Claim, 1 Drawing Sheet
